UNITED STATES PATENT OFFICE.

ALFRED A. ADLER, OF NEW YORK, N. Y., AND HARRY ALBERTMAN, OF PHILADELPHIA, PENNSYLVANIA, ASSIGNEES TO JACQUARD KNITTING MACHINE CO., INC., OF UNION HILL, NEW JERSEY, A CORPORATION OF NEW YORK.

KNITTING MACHINE.

Application filed September 9, 1920. Serial No. 409,201.

Our invention relates to knitting machines and is directed to the production of knit fabric incorporating patterns or designs of all kinds, i. e., fancy fabrics in general.

5 Circular knitting machines with pattern mechanisms of the types heretofore used can be adapted to produce a certain limited variety of regular patterns, but are incapable of producing, in a practical manner and for 10 the every day purposes of commerce, a complicated design requiring more than a few dissimilar courses or rows of stitches to complete it. Flat knitting machines have been used to produce more complicated designs, but the process with flat machines is 15 a slow and expensive one. Therefore the production of brocade-like patterns for example, has been left exclusively to the art of weaving where the construction of the pattern or design may be controlled effectively 20 by a chain of perforated paper cards adapted to control the formation of every stitch, if desired, and in which art accordingly the design may be of any complexity and substantially any size lengthwise of the cloth. 25 One of the principal features of our invention is that we have discovered a manner of combining a paper pattern with a knitting machine that is wholly practical and 30 highly economical, especially in connection with circular knitting machines, and have thereby made it possible to produce readily, on circular knitting machines, the most intricate patterns and patterns which it has heretofore been impossible to produce practically 35 on circular machines. The invention also involves other matters as hereinafter appears.

The invention will be best understood 40 from a description of a machine embodying it. In the accompanying drawings:

Fig. 1 is a central sectional view of a circular knitting machine embodying the invention.

45 Fig. 2 is a plan view of the same.

Fig. 3 is a plan view of one of the units or sections of the pattern mechanism taken on the line 3—3 of Fig. 1.

Fig. 3^a is a perspective view of a needle-jack of Fig. 1.

Fig. 4 is a sectional view of a unit or section of the pattern mechanism, the ratchet thereof being shown in elevation.

Fig. 5 is a substantially similar sectional

view showing the ram of the unit in depressed position.

55 Fig. 6 is another sectional view of the same taken substantially on the line 6—6 of Fig. 4.

Fig. 7 is a detail, in end elevation, showing the latch for holding the platen shaft 60 in place in one of the pattern units.

Fig. 8 is a diagrammatic elevation showing a development of the cams of a single feed or operating group and indicating the relation of the cams to one another and to 65 the needles and needle-jacks.

Fig. 9 is a similar view showing the cams in a more advanced position with respect to the same pattern unit.

Fig. 10 is a further diagrammatic view 70 showing the cams in a still more advanced position, and

Figs. 11 to 14 are views showing several 75 relative positions of the needles and yarn in the machine illustrated.

In these drawings the invention is illustrated with reference to a circular knitting machine of standard type, the needles being of the latch type and the organization being such that the design is distinguished from 80 the background by the use of two different kinds of stitches, i. e. tuck and plain knit stitches. In the production of "knit" stitches the needle operation is that shown in Figs. 11 and 12. At the beginning of the 85 formation of a new "knit" stitch, the needle 11 is raised so high that the latch 13 clears the previous loop 14; the thread is then laid against the needle (as indicated at 15, Fig. 11) and subsequently the needle is caused to 90 descend. In its downward movement the hooked end of the needle catches the thread 15 (as shown in Fig. 12) and the further descent of the needle through the loop 14 of a prior stitch, causes this loop to close the 95 latch 13 and thus permits this loop to slip over the top of the needle, thus leaving a new loop 14, formed of the thread 15, hanging on the needle when the needle rises again.

The manner in which "tuck" stitches are made is illustrated in Figs. 13 and 14. In this case the needles are not raised quite high enough to enable the end of the latch 13 to clear the prior loop 14 (Fig. 13). Upon the descent of the needles from this "tuck" position, the hooked end of the needle 11 not only carries with it the new-laid thread 15 but it also contains the previous 100 105

loop 14 (Fig. 14) since the old loop 14 is not now permitted to slip over the top of the needle. Both loops are thus retained in the needle until such a time, during a subsequent operation, when the needle is elevated to the knitting position of Fig. 11. When this occurs the following descent of the needle will cause the formation of at least a double loop 14, the original number 14 being allowed to slip over the top of the needle along with the thread or threads laid therein subsequently.

The principles of these stitches are well understood. In the machine of Figs. 1 to 10, there is the usual cylinder 10 vertically grooved for the reception of and constituting the bed of a bank or series of latch needles 11. A cam 20 is arranged to raise all the needles to "tuck" height as shown in Figs. 1 and 8. In addition a master pattern mechanism is provided through the agency of which any needle may be raised still higher, namely to the "knit" stitch position. Accordingly, any one of the needles may at any one of its operations, according to the dictates of the pattern controlling element, function to produce either a knit stitch or a tuck stitch and the result of these diverse stitches will be the desired design in the final finished knitted fabric. The stitch cam 21 retracts all the needles to their lowermost position (Fig. 14) to complete the stitches.

The master pattern mechanism is divided into a number of sections 28 (see Fig. 2) in the machine illustrated. There may be any number of these units or sections so long as they are in sufficient number to assure the exercise of the pattern-control on each controllable needle in advance of each feed the action of which is intended to be modified by the pattern mechanism; this will be understood better after the operation is described. The sections are preferably distributed around the cylinder in order to bring the pattern mechanism into direct relation with every controlled needle, being equiangularly distributed if every needle, or equiangularly distributed needles are to be controlled. It will be observed that each section of this mechanism includes one of the belt-like sections 12 into which the pattern-controlling element is divided. These pattern sections are perforated in accordance with the design to be knitted into the fabric as will also be understood from the matter hereafter.

As shown in Fig. 1, the needle cylinder is elongated or made somewhat longer than usual, and a series of needle-lifting jacks 22 are arranged in the knitting cylinder grooves 23, one below each of the needles to be controlled by the pattern. In effect, these are extensions of, or elongate the needles, and this permits the preferred placing of the pattern mechanisms outside of the needle cyl-

inder and underneath the machine bed-plate as shown in Fig. 1. In the present instance, these jacks are adapted to be lifted in part by the pattern mechanism and in part by a jack cam 24 (Fig. 8) which is also carried by the cam ring 31 which carries the needle cams 20 and 21. Fig. 10 shows that the position of the lifting cam 24 with respect to the projections or butts 25 of the jacks is such that if the jacks remain in their lowermost position they will not be engaged by the cam 24, but if any jack be given an initial upward movement by the pattern mechanism so as to bring its butt above the level of the point 26 of this cam then such jack will be raised by the cam and will lift the corresponding needle to "knit" position, i. e. its latch will be carried through the fabric. The cam 24 is also a needle raising cam therefore. The jacks 22 are raised initially, i. e., above the point 26, by jack levers 27 which are grouped into and form parts of the several pattern-control sections or units 28. These levers are placed substantially radial of the cylinder bed of the needles (Fig. 8), and their pivot bearings are supported in a fixed position with respect to the cylinder wherein the inner end of each lever extends into a slot in the needle cylinder and underneath a jack (Fig. 1). They may vary in length to correspond to the curvature of the needle cylinder (see Fig. 3). Above the outer ends of the jack levers 27 a ram 29 is provided in each of the sections 28 to operate the jack levers thereof (Figs. 1, 3, 4 and 5). These rams are vertically controlled by the cam 30 (Figs. 5, 8, 9 and 10) which is secured to the under face of the cam ring 31 and serves to depress the rams of all the sections 28 successively, or progressively around the machine, as the cam cylinder rotates. This cam engages the anti-friction rollers 32 on the upper ends of the plungers 33. The space between the outer ends of the jack levers 27 and the ram 29 is such however that the levers 27 will not be directly engaged thereby, but the connection may be completed selectively by a series of selector levers 35 (Figs. 1, 3, 4, 5 and 6) of which there is one for each of the jack levers 27. These selector levers 35 are also grouped into and form parts of the units 28 (see Figs. 1 and 3). The slots 38 therein permit the selector levers to move longitudinally into and out of connection-completing position underneath the ram, as well as turn on their fulerums or transverse supporting pins 37, and each one is under the control of a spring 39 which normally holds its selector retracted from connection-completing position. Each selector 35 is further provided with a feeler which may be an integral finger 38, and the springs 39 are slightly inclined (Fig. 4) so as to also pull the feeler fingers down lightly toward

the pivoted platen roller 40, of which there is one in each unit, or section 28. This platen roller 40 carries the portion 12 of the pattern-controlling element allotted to its 5 section or unit 28, and is provided with longitudinal grooves 41 with which the perforations in the pattern-controlling element 12 are arranged to coincide as the platen is turned and the element 12 advanced and new 10 perforations are brought underneath the group of feelers. Accordingly whenever a perforation in the pattern-controlling element is presented to a feeler, that feeler is pulled down through it and into one of the 15 grooves 41. But whenever an unperforated portion of the pattern sheet 12 lies underneath a feeler, then that feeler is pressed lightly and only lightly, against the pattern sheet and the latter holds the feeler elevated 20 and out of the cylinder groove.

The perforations or pattern calling agencies are arranged in rows crosswise of the pattern-controlling element as appears in Fig. 6. Likewise the feelers are arranged 25 in a row crosswise of the pattern-controlling element as has appeared hereinbefore. Those selectors whose feelers 38 find perforations in the pattern sheets 12 and fall into the grooves 41 of the rollers are pushed forward successively by the successive turning of the platens, one after another, into connection-completing position underneath the rams 29. To this end the platens 40 are rotated successively, and step-by-step, by means 30 of pawls 43 carried on the plungers 44 which are depressed successively by the cam 45. This cam is also secured to the under side of the cam ring 31 (Fig. 1) along with the cam 30. When one of the plungers 44 is 35 moved downwardly by the cam 45 its platen roller 40 is first rotated through a sufficient are to cause the engaged selectors 35, that is to say, those whose feelers 38 have found perforations in the pattern sheet and passed downwards into a groove 41 of that platen, to be projected between the ends of the corresponding jack levers 27 and the ram 29. The other selectors remain retracted. Thus 40 in Fig. 1 (compare with Figs. 4 and 5) the platen roller 40 is shown at rest, and the feeler finger 38 of one of the selectors 35 is within one of the grooves 41 of the platen, while the corresponding finger of another selector is held above said groove by an imperforate portion of the local section 12 of the pattern-controlling element. The pawl 43 is thereupon pushed down by the cam 45 until the position shown in Fig. 4 is reached. That selector 35 whose feeler finger 38 rested 45 on an imperforate portion of pattern 12 still remains in the position in which it was in Fig. 1, i. e., retracted and inactive. The other selector 35 however whose feeler finger 38 was engaged by the groove 41, has moved forward until its upward projection

46 lies inward of the ram 29. The ram 29 is now pushed down by the cam 30 (note the relation of cam 30 to cam 45 in Fig. 8) and this brings the parts into the position shown in Fig. 5. In that figure that or those 50 selectors 35 which have been moved forward into a position where they can be acted upon by the ram 29, have been pushed downwardly upon the corresponding jack levers, causing the corresponding jacks 22 to be raised until their butts are now above the level of the point 26 on cam 24. This action (i. e., the tipping or turning of the advanced 55 selectors) has lifted the feeler fingers 38 out of the grooves 41 but the projections 46 of these selectors 35 (engaging the ram) temporarily prevent the springs 39 from drawing these selectors back. The cam 45 now depresses the plunger 43 still farther (note the shape of this cam in Fig. 8) thus bringing another groove 41 and row of perforations underneath the line of feeler fingers 38. The cam 30 now passes off the roller 32 (and cam 45 off the plunger 44) and the spring 50 (Fig. 3) returns the ram to its 60 upper position. This releases the projected selectors 35 of this pattern section and permits their spring 39 to draw them backward to the position of Fig. 1, in which position another selection of all the selectors of this 65 group is made by its pattern section 12; such feelers as now find perforations below them fall into the new groove 41, or if the pattern-controlling element is entirely imperforate at that point, they all remain out of 70 action.

The parts having been gotten into the position shown in Fig. 5 as before described, some of the jacks 22 are in elevated position as explained and presumably others have remained in their normal or lower position. In other words, a relation is brought about such as is shown in Fig. 9. While the cam 30 holds the ram 29 depressed and certain jacks elevated with their butts raised above the point 26 of the cam 24, the cam 24 comes into play and raises all raised jacks 22 still farther, and thus raising the corresponding needles 11 to the knitting position as shown in Fig. 10. From Figs. 9 and 10 it will be 105 observed that the length of cam 30 and its relation to cam 24 are such that each ram 29 is held depressed until the cam 24 has reached the last jack related to the respective ram. This is to assure that the butt of each raised jack is above the point 26 when the cam 24 reaches it. The jacks 22 which were not acted upon by their jack levers 27 are not affected by the cam 24, and the needles 11 corresponding to these latter jacks 110 are only raised to the tuck position by the cam 20. In the usual manner yarn is now laid in all the needles by the yarn guide of the same feed, that is to say, by the yarn guide (shown in Fig. 1) coacting with the 115

group of needle raising and stitch cams discussed, and thereafter the stitch cam 21 retracts all the needles and thereby causes the formation of the appropriate stitches. The cam 54 restores all the jacks 22 to their normal or lower level.

A latch 51, (Fig. 7) may be conveniently employed to facilitate the temporary removal of the platen 40 from its bearings which hold it (or rather hold its axis) in a fixed relation to the coacting group of feelers 38. The platen is made readily removable in order that new pattern sheets 12 may be substituted. The end of the platen shaft opposite the ratchet 42 may be grooved circumferentially to receive the latch 51 which is hinged on the frame as shown, and which thus secures the platen in the machine. By raising the latch 51 the shaft may be withdrawn, the platen taken out, and another pattern section 12 substituted. Spring 55 will hold the plunger 44 against its cam 45. This spring 55 (see Fig. 1) is carried in a bracket on the frame and the lower end of the plunger 44 rests upon it. Springs 50 hold the rams 29 against the plungers 33 and these plungers against the cam 30.

By reference to Fig. 2, it will be observed that the arrangement which has been adopted is such that while it allows each individual needle to be individually acted upon in a selected fashion, ample room between each two units 28 is provided for the operating mechanism, i. e. in this instance the plunger 44, pawl 43, and ratchet 42, the latch 51, bracket for spring 55, etc.

The platen 40 is shown as a rotatable cylinder with grooves, but obviously a pattern support of a different type may be employed to accomplish the same results. We have found it desirable, however, that the pattern sections 12 pass around supports which have fixed axes near the feelers, as in the construction shown, so that the pattern sections 12 are simply pulled around like a belt, without oscillation. Furthermore, such a construction minimizes the wear of the pattern sheets under the action of the feelers, and entails a longer life for the pattern sheets 12 than some other possible constructions, and is a construction which is particularly well adapted for knitting machines as will be understood.

The angular relation of the various cams to each other around the axis of the needle cylinder, which determines the order in which they act, is shown in part in Fig. 1 but more completely in Fig. 8. Summarizing the operation of the machine as a whole with respect to the single feed shown, its action is as follows: A suitable pattern sheet 12 is first prepared and a section placed on each grooved platen 40; pins on the ends of the platens and corresponding holes in the edges of the section 12 cause the patterns 12

to advance with the turning of the platens. The pattern-controlling perforations in the pattern controlling element 12 are placed in such a relation to these edge holes that the perforations always fall above the plateau 70 grooves 41, as before indicated. The different sections of the pattern controlling element 12 may be perforated alike or differently for the various units 28 according to the design to be produced. When the pattern sections 75 12 are in place, such feelers 38 as find perforations therein fall into grooves 41 of the various platen drums 40. As the cam ring 31 is now rotated by means of the bevelled pinion 47 which engages the circular rack 80 48 on the cam ring 31 (Fig. 2), the feeding cam 45 first turns one of the platen rollers 40 through approximately one-sixteenth of a revolution (since there are eight grooves 41 in each of the rollers 40 shown). This 85 brings the parts of the said pattern unit 28 from the position shown in Fig. 1 to the position shown in Fig. 4, i. e., the wall of the groove 41 of the turning platen has pushed against the feeler fingers that are within it 90 and has pushed the corresponding selectors 35 into operative position between the ram 29 and the jack levers 27. Continued turning of the cam ring 31 now causes the ram 29 of the same pattern section to be thrust 95 downward by the cam 30 and brings the cam 45 into operation on the next succeeding section 28. In the first mentioned section 28 the depression of the ram 29 brings about the relation of parts shown in Fig. 5, i. e., 100 the initial elevation of the corresponding jacks 22 and the lifting of the fallen feelers 38 out of the groove in the platen. The platen is now given a further rotation of about one-sixteenth of a revolution (by cam 105 45) to bring a new groove 41 into feeler engaging position and the cams 45 and 30 then pass off the plungers 44 and 33 of the first mentioned section 28, the ram 29 rises, and the projected selectors 35 are returned by 110 their springs to the selection-making position of Fig. 1. While the cam 30 is holding the ram 29 depressed in the first mentioned section 28, the cam ring 31 brings the cam 24 to the jacks 22 of this part of the machine and such of those jacks 22 as have been raised by the levers 27 are now raised still higher by this cam 24 and the corresponding needles are thereby raised to "knit" position, the other needles of this portion of 115 the machine remaining in "tuck" position (Fig. 10) as before stated. The yarn guide now passes the needles corresponding to this first mentioned section 28, laying yarn in all of them and the raised jacks are then successively retracted by cam 54 while the needles are successively retracted by the stitch cam 21 to form the appropriate stitches. The result of these operations is 120 that some of the needles of this portion of 125 65 edges of the section 12 cause the patterns 12

the knitting machine (i. e., those whose complexity and great length of repeat may be produced on a commercial basis, that is to say, reliably and comparatively cheaply, since the mechanism is such that the pattern-controlling element 12 may be made of paper or other similarly light, thin materials and since very large pattern elements of such materials are readily handled on or with the machine without rendering the whole device impractical and generally non-commercial. Furthermore, pattern sheets of light thin materials like paper are easily and cheaply made, so that a manufacturer may offer a larger variety of fabrics to his customers, and may make up new designs at little expense. Patterns in the form of endless belts like each of the pattern sections 12 (see Fig. 1) are especially adapted for the work. We have made these thin, paper-light, mechanically weak, materials available for pattern-controls by using mechanisms therewith which leave to the pattern-controlling elements 12 only, or substantially only, the bare function of directing the knitting processes, all the operations subsequent to the bare call of the pattern-controlling element on the feelers, that is to say, the operations which require the exertion of any considerable force, being performed by other elements than the pattern element. Thus no considerable labor is imposed on the pattern and mechanically weak or paper-light materials are made suitable. The foregoing is illustrated in the machine shown in the drawings where the pattern-controlling element 12 is required simply to support the light pressure of the feelers 38, and all the operations subsequent to the call of the feelers (by the feelers falling into the pattern perforations) are brought about by other elements of the device operating around the machine progressively in advance of the respective feed passes, beginning with the platens successively pushing against the feelers that find perforations and thereby pushing the corresponding selectors forward. In toto, it will be observed that we have adapted principles of the well-known weaving Jacquard mechanism (as heretofore employed in the art of weaving) to knitting machines generally.

By the term "feed" it will be understood that we refer to a yarn guide and the group of respectively associated members (customarily cams) which project and retract or otherwise actuate the stitch-forming elements in coordination with it; each complete individual pass or complete revolution of a feed about the machine axis adds a course or row of stitches to the fabric, some of which may be welt stitches, however, and the place of the welt later further occupied with a stitch of another variety by a subsequent passage of a feed, as will be understood. Where welt stitches are to be em-

the knitting machine (i. e., those whose complexity and great length of repeat may be produced on a commercial basis, that is to say, reliably and comparatively cheaply, since the mechanism is such that the pattern-controlling element 12 may be made of 70 paper or other similarly light, thin materials and since very large pattern elements of such materials are readily handled on or with the machine without rendering the whole device impractical and generally non-commercial. Furthermore, pattern sheets of light thin materials like paper are easily and cheaply made, so that a manufacturer may offer a larger variety of fabrics to his customers, and may make up new designs 75 at little expense. Patterns in the form of endless belts like each of the pattern sections 12 (see Fig. 1) are especially adapted for the work. We have made these thin, paper-light, mechanically weak, materials available for pattern-controls by using mechanisms therewith which leave to the pattern-controlling elements 12 only, or substantially 80 only, the bare function of directing the knitting processes, all the operations subsequent 85 to the bare call of the pattern-controlling element on the feelers, that is to say, the operations which require the exertion of any considerable force, being performed by other elements than the pattern element. Thus 90 no considerable labor is imposed on the pattern and mechanically weak or paper-light materials are made suitable. The foregoing is illustrated in the machine shown in the drawings where the pattern-controlling element 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895

It may now be observed that knitted fabrics incorporating designs of the greatest

ployed, the cam 20, as a means raising the needles to "tuck" position, is omitted, with the result that no needle is raised to a yarn-receiving position except when its action is initiated by the pattern mechanism.

It will be observed that our invention is not limited to the lifting of latch needles but it may be applied to other types of elements forming or assisting in the formation

10 of the stitches. Furthermore it is not limited to the production of designs or fancy effects through the agency of knit and tuck stitches; inasmuch as it provides means for causing each stitch forming element to act 15 on yarn only as and when desired, the invention may be utilized for the production of fabrics and designs in numerous ways that will occur to those skilled in this art. Also it is not essential that each feeler coact 20 with a single stitch-forming element although a feeler for every individual element produces a design having the clearest and most definite outline and affords the greatest possible degree of independent 25 action to the stitch-forming elements, and hence the greatest variety in design or patterns. Where designs are to be equally producible throughout any and every part of the width of the cloth the pattern-controlled 30 stitch-forming elements must be distributed, that is to say, substantially regularly placed, throughout the whole of the needle bed, e. g. substantially equiangularly placed around the needle cylinder of a circular machine. These and other modifications are 35 within the scope of our invention as appears from the appended claims.

We claim:

1. The combination in a knitting machine, 40 of a circular bank of stitch-forming elements, a pattern-controlling element, a plurality of feelers to co-act therewith, couplings extending from said feelers to control the action of said stitch-forming elements, and other means to actuate said 45 couplings in accordance with the call of the pattern-controlling element on the feelers, said means being so timed with respect to the formation of stitches that said means 50 can actuate each coupling intermediate the completing of loops by the respectively corresponding stitch-forming element and while other stitch-forming elements are completing loops.

55 2. The combination in a knitting machine, of a circular bank of stitch-forming elements, a pattern-controlling element, a plurality of feelers to lightly engage therewith, couplings extending from said feelers 60 to control the action of said stitch-forming elements, and other means, independent of the pattern-controlling element, for actuating said couplings to control the action of the stitch-forming elements in accordance with 65 the call of the feelers by the pattern-con-

trolling element, said means being arranged to actuate the whole of the structure comprising each coupling so that the pattern-controlling element has substantially only the duty of selecting between feelers bearing 70 against it, and said means actuating the selected couplings progressively, round and round the machine, while the cam cylinder rotates in one direction.

3. The combination in a circular knitting 75 machine of the circular bank of stitch-forming elements, a group of feelers mounted on the knitting machine at the side of the needle cylinder, a perforated pattern-controlling element occupying a fixed position 80 with respect to the group of feelers, the feelers being adapted to enter the perforations therein, means for advancing the pattern-controlling element, to make the new calls on the feelers, coupling members engaging the 85 feelers for differentiation among themselves by the entry of feelers into the perforations in the pattern-controlling element, and a cam revolving around the axis of the needle cylinder to actuate differentiated couplings 90 to cause the stitch-forming elements to act in accordance with the call of the pattern-controlling element.

4. In a knitting machine, the combination 95 of a circular bed for stitch forming elements, a pattern-controlling element therefor, feelers, the feelers and the pattern-calling agencies of the pattern-controlling element being arranged in rows substantially cross-wise of the latter, couplings relating the feelers to said bed to control the 100 action of the stitch-forming elements, and other means to move the couplings to control the stitch-forming elements, said means being arranged to actuate the couplings progressively while the machine is forming 105 stitches but being so timed in its action that each coupling to be moved to affect the formation of a stitch, is moved in advance of the completion of the loop of said stitch.

5. The combination with a knitting machine, having stitch-forming elements arranged in a circular bank, of a perforated pattern-controlling element of elongated form having its perforations arranged in 110 rows crosswise of itself, feelers adapted to reach into the perforations and thereby be called in various combinations, said feelers being coupled to the stitch-forming elements to control their action, means for advancing 115 the pattern-controlling element lengthwise to bring successive pattern perforations to the feelers while said stitch-forming elements are forming stitches, and other means performing the subsequent operations consequent on the said calling of the feelers so that the said pattern-controlling element performs substantially only the bare function of directing the knitting processes, said last mentioned means operating simultaneously 120 125 130

with the formation of stitches but being timed to exercise its control at different points around the circular machine separately and at each point exercising its control 5 while the knitting is interrupted for the moment at this point.

6. In a circular knitting machine, the combination with a circular bank of stitch-forming elements, of a pattern-controlling element, having its pattern calling agencies arranged in rows substantially crosswise of itself, feelers to coact therewith, couplings reaching from the respective feelers to affect the operation of the stitch-forming elements, 10 means for advancing the pattern element while stitches are being made, and other means for actuating said couplings by groups seriatim in accordance with the call of said pattern-controlling element on said 15 feelers to effect the control of the respective stitch-forming elements, said last mentioned means actuating each selected coupling while stitch-forming elements corresponding to preceding couplings are completing 20 stitches.

7. In a circular knitting machine, in combination with a circular bank of needles and a stitch cam, of a pattern-controlling element of elongated form, to be advanced 25 lengthwise while the stitch cam is acting on the needles, a plurality of feeler members arranged in groups, the feeler members of each group coacting simultaneously with the pattern element, couplings extending from the feelers, and other means for actuating 30 all the couplings that are to be actuated to cause the needles to operate in accordance with the pattern-controlling element, the pattern element making its calls on the 35 groups of feeler members progressively around the machine in the formation of individual rows of stitches and making its calls on each group while the stitch cam is operating on the needles coupled to a preceding group.

8. In a knitting machine, the combination of stitch-forming elements, a pattern-controlling element, a plurality of feelers to coact therewith, said feelers and the pattern- 50 calling agencies of the pattern-controlling element being arranged in rows substantially crosswise of the latter, a coupling means for coupling each of said feelers to a stitch-forming element so as to control the action thereof, and other means for actuating progressively, in the formation of individual 55 rows of stitches, those of said couplings that are called by the action of the pattern-controlling element on the feelers.

9. In a knitting machine, the combination with a circular bank of stitch-forming elements, pattern-controlling means having its pattern-calling agencies arranged in rows substantially crosswise thereof, a plurality 60

of feelers arranged for coaction therewith, 65 said pattern-controlling means calling progressively, while said machine is forming stitches, those feelers which are to be called to control an individual row of stitches, a coupling means for coupling each of said 70 feelers to a stitch-forming element so as to control the action thereof, and other means for actuating the couplings progressively in the formation of individual rows of stitches, and after the call of respectively corresponding feelers by the pattern-controlling 75 means, to effectuate the control of the stitch-forming elements.

10. In a knitting machine, the combination of a circular bank of stitch-forming elements, a stitch cam revolving about the axis of said bank continuously in one direction, a pattern-controlling element, a plurality of feelers for coaction therewith for call thereby, a coupling for coupling each 80 of said feelers to a stitch-forming element, and a cam revolving around the axis of said bank synchronously with said stitch cam for actuating couplings selected by the action 85 of the pattern-controlling element on the 80 feelers to cause the stitch-forming elements to act in accordance with the call of the pattern-controlling element, said cam actuating the couplings progressively in advance 90 of the action of said stitch cam on the corresponding stitch-forming elements and subsequent to the action of the pattern-controlling element on the corresponding feelers. 95

11. In a knitting machine, the combination of a plurality of stitch-forming elements, a circular bed therefor, a cam ring having a stitch cam rotating about said bed continuously in one direction, a pattern-controlling element having its pattern calling agencies arranged in rows substantially 100 crosswise of itself, a plurality of feelers for engagement therewith, a coupling for coupling each of said feelers to a stitch-forming element to affect the action thereof, said couplings having members distributed around 105 the axis of and outside said bed of the stitch-forming elements, and a cam revolving around the axis of said bank synchronously with said cam ring to actuate the said members of the couplings to cause the 110 stitch-forming elements to act in accordance with the call of the pattern-controlling element on the feelers and while the cam ring is rotating as aforesaid, the last mentioned cam actuating said coupling members subsequent to the call of the corresponding feeler 115 by the pattern-controlling element. 120

12. In a knitting machine, the combination of a circular bank of stitch-forming elements, a pattern-controlling element, a plurality of feelers to coact with said pattern-controlling element for call thereby, couplings for coupling said feelers to the stitch- 125

forming elements and controlled by said feelers, each of said couplings including a lever and said levers being substantially uniformly distributed around the axis of the 5 bank of stitch-forming elements, and a cam revolving about said axis continuously in one direction to move said levers in accordance with the call thereof by the feelers, the pattern-controlling element being advanced 10 to bring new calls to the feelers while said cam is revolving to effect the action of the stitch-forming elements.

13. In a knitting machine, the combination of a circular bank of stitch-forming elements, a pattern-controlling element, a plurality of feelers which coact with said pattern-controlling element for call thereby, a lever and jack between each of said feelers and a stitch-forming element through which 20 the control of the stitch-forming element is exercised, other means for operating the levers progressively around said bank in accordance with the call of the feelers by the pattern-controlling element, said other means 25 making a number of successive passes around the machine, all in one direction, while new calls are being made but being so timed as to operate each selected lever subsequent to the action of the pattern-controlling element on the corresponding feeler, and a cam 30 revolving about the axis of said bank for moving the jacks as selected by said operation of the levers and thereby moving the corresponding stitch-forming element.

14. In a circular knitting machine, the combination with a circular bank of stitch-forming elements and a cam revolving about the axis of said bank to engage said stitch-forming elements to retract the same, of a 40 pattern-controlling element, a plurality of feelers to coact with said pattern element for call thereby, said feelers and the pattern-calling agencies of the pattern-controlling element being arranged in rows substantially crosswise of the latter, couplings between said feelers and stitch-forming elements, a cam revolving about the axis of said bank of stitch-forming elements to actuate members of said couplings when 45 advanced into its path, to make their control manifest on the projection of stitch-forming elements to yarn-engaging position, and means for advancing feeler-selected couplings to bring members of the couplings 50 into the path of the last mentioned cam, said means advancing the selected members progressively and in advance of said last mentioned cam while said cams are making repeated complete revolutions about said bank 55 axis in one direction.

15. In a knitting machine, the combination with a bed for stitch-forming elements and a cam to engage the stitch-forming elements to retract the same, of a pattern-controlling element, a plurality of feelers to coact with said

pattern element for call thereby, couplings relating said feelers to said bed column, other means for moving couplings selected by the feelers to cause chosen couplings to be in advanced position with members of the 70 couplings in control-manifesting position, and another means for actuating said advanced coupling members to make the control manifest on the stitch-forming elements.

16. In a knitting machine, the combination 75 with a bed for stitch-forming elements, means to project said elements to engage the yarn, and means to retract said elements at the completion of the formation of stitches, of a pattern-controlling element, a plurality 80 of feelers to coact with said pattern-controlling element for call thereby, couplings relating said feelers to said bed, other means for moving those couplings which are selected by the action of said pattern 85 controlling element on the feelers to bring members of such couplings to positions wherein the control of the stitch-forming elements may be effected, and another means for moving the said moved coupling members to control the projection of the stitch-forming elements by the first mentioned means.

17. In a knitting machine, the combination with a bed for stitch-forming elements 90 and means to retract the stitch-forming elements at the completion of stitches, of a pattern-controlling element, a plurality of feelers which coact therewith for call thereby, couplings relating said feelers to said bed, other means for moving those couplings 95 which are selected by the action of the pattern-controlling element on the feelers to bring members of such couplings into the path of the means hereinafter mentioned, and another means for moving the said 100 moved coupling members and thereby bringing about the projection of the corresponding stitch-forming elements to yarn engaging position.

18. In a knitting machine, a bank of 110 stitch-forming elements, a pattern-controlling element therefor, a plurality of feelers for simultaneous call by the pattern-controlling element, couplings extending from said feelers, other means to move the couplings selected by the action of the pattern-controlling element on the feelers to bring members of such couplings to positions in which the action of the corresponding stitch-forming elements may be brought about and 115 to hold said members in such positions, and another means to move the stitch-forming elements corresponding to the moved couplings, each said moved member being held in said moved position by said holding means 120 until the last mentioned moving means has retracted the stitch-forming element corresponding to the respective coupling member.

19. In a knitting machine, a bank of stitch-forming elements, jacks for said elements, 130

- a pattern-controlling element, a plurality of feelers for call thereby, couplings extending from said feelers, other means to actuate the couplings in accordance with the call of said 5 pattern element on the feelers to project the corresponding jacks and to hold the projected jacks in projected position, and another means to actuate the stitch-forming elements corresponding to the projected 10 jacks, said holding means holding each projected jack in its projected position until said means for actuating the stitch-forming elements has reached the corresponding stitch-forming element.
- 15 20. In a knitting machine, the combination of a circular bank of stitch-forming elements, a yarn guide to revolve about the axis thereof, a pattern-controlling element for said bank, a plurality of feelers for 20 simultaneous call thereby, means relating each of said feelers to a stitch-forming element, other means for actuating said relating means in accordance with the call of said feelers to cause movement of the respectively 25 corresponding stitch-forming elements toward yarn engaging positions, and a cam revolving around the axis of said bank of stitch-forming elements, continuously in one direction at the same speed as said yarn 30 guide, to complete the movement which brings those stitch-forming elements corresponding to the actuated relating means to yarn engaging positions.
21. In a knitting machine, the combination 35 of stitch-forming elements, a pattern-controlling element, feelers for call thereby, couplings extending from the feelers and comprising pivoted bars engaging said feelers and arranged to turn on their pivots as 40 the respective feelers actuate in accordance with the call of said pattern-controlling element, and other means to move, the bars of those couplings which are differentiated from the remainder of the couplings by some 45 of the bars being turned on their pivots in accordance with the call of the pattern-controlling element, said means moving said bars longitudinally to effect the control of the corresponding stitch-forming elements.
- 50 22. In a knitting machine, the combination of a circular bank of stitch-forming elements, a plurality of sections of a pattern-controlling element arranged around the axis of said bank, a plurality of feelers for call 55 by each of said sections, couplings relating said feelers to the stitch-forming elements and each including a pivoted bar supported substantially radially of the axis of said bank and engaging a feeler so as to turn on 60 its pivot on the actuation of its feeler at a call by the pattern-controlling element, and other means to move said bars longitudinally, said means acting on those bars which are differentiated from the remainder of the 65 bars by some of the bars being turned on
- their pivots under the call of the pattern-controlling element, and said means acting on such bars progressively, round and round said circular bank, as the feed of the machine makes repeated one direction revolutions 70 round said bank.
23. A pattern mechanism for knitting machines having in combination a recessed rotating platen drum, a perforated pattern sheet cooperating with said platen, a plurality of selectors movable pivotally and longitudinally and having feelers arranged to pass through the pattern sheet perforations and enter the platen recesses, such selectors as enter the recesses being moved 75 longitudinally by the platen, as the latter rotates, and means cooperating with the projected selectors to turn them pivotally and to retract the feelers from the platen recess.
24. A knitting machine comprising in combination stitch-forming elements carried in a cylinder, controlling mechanism for said elements comprising levers arranged in groups about the cylinder, actuating means for each group of levers comprising a ram, 80 selector members, and pattern means for causing predetermined selector members to be located in cooperative relation between the ram and levers so that the corresponding levers may be actuated by the ram, and 85 means for actuating the rams and advancing said pattern means to make new selections from the selector members.
25. A Jacquard type knitting machine comprising in combination a grooved cylinder, 90 latch needles in said grooves, actuating mechanism for the needles comprising levers arranged in groups circumferentially about the lower end of the needle cylinder, actuating means for each group of levers comprising a ram, selector members, and mechanism for causing selected selector members to be located in cooperative relation between the ram and levers whereby the corresponding levers may be actuated by the ram, and 95 cam means revolving around the needle cylinder for actuating the rams.
26. A Jacquard type knitting machine comprising in combination a grooved cylinder, 100 latch needles and needle-jacks in said grooves, actuating mechanism for said jacks comprising jack-levers arranged in groups circumferentially about the cylinder, actuating means for each group of said jack levers comprising a ram, 105 selector, a pattern mechanism for causing selected selectors to be located in co-operative relation to the ram and jack-levers, a member for actuating said ram and a second member for actuating the pattern mechanism step by step.
27. In a knitting machine, the combination 115 of a circular bed for stitch-forming elements, a cam for projecting said elements, a stitch cam for retracting said elements, said cams revolving around the axis of said bank 120
- 125
- 130

of stitch-forming elements continuously in one direction, a pattern-controlling element, a plurality of feelers for call thereby, couplings relating said feelers to said bed, and 5 other means to move the couplings progressively in accordance with the call of the pattern-controlling element on the feelers and respectively in advance of the action of the first mentioned cam on the corresponding 10 stitch-forming elements, to control the action of said first-mentioned cam on the stitch-forming elements.

28. In a knitting machine, the combination of a circular bed for sliding needles, a raising 15 cam for raising the needles, a stitch cam for retracting the needles from such positions to complete the stitches, said cams revolving around the axis of said needle bank continuously in one direction, a pattern-controlling 20 element, a plurality of feelers to contact therewith for call thereby, said feelers and the pattern calling agencies of the pattern-controlling element being arranged in rows substantially crosswise of the latter, 25 a coupling relating each of said feelers to said bed, and other means to actuate said couplings in accordance with the call of the feelers to cause said raising cam to raise the corresponding needles, said means acting on 30 the couplings progressively in individual revolutions of the cams and in advance of the action of the raising cam.

29. In a knitting machine, a circular bank of stitch-forming elements, a pattern-controlling 35 element, feelers for call thereby, couplings extending from and controlled by said feelers, and a cam ring rotating continuously in one direction around said bank, said cam ring carrying a cam to project the 40 stitch-forming elements, a stitch cam in the rear of said projecting cam, other means to actuate the feeler-selected couplings to control the action of said projecting cam on the corresponding stitch-forming elements, and 45 means to advance the pattern-controlling element, said coupling actuating means actuating the couplings subsequent to their selection by the feelers and prior to the action of said retracting cam on the corresponding 50 stitch-forming elements.

30. In a knitting machine, the combination of a circular bank of stitch-forming elements, a pattern-controlling element, feelers for call thereby, couplings extending 55 from and controlled by said feelers, a cam ring to actuate said stitch-forming elements, said ring rotating around said bank of stitch-forming elements continuously in one direction, and means carried by said 60 ring to actuate said couplings progressively, as the couplings are called by the feelers, to effectuate the control of the pattern-controlling element on the stitch-forming elements.

31. In a circular knitting machine for the

knitting of fancy fabrics, a circular bank of 70 stitch-forming elements, a pattern-controlling element perforated in accordance with the fancy effect to be produced, a plurality of feelers for coaction therewith and ar-

ranged to move into the perforations therein as perforations are presented to the individual feelers by the pattern, the feelers thereby being differentiated to direct the 75 action of the stitch-forming elements, and 80 said feelers and perforations being arranged in rows substantially crosswise of the pattern-controlling element, couplings extending from the feelers to affect the action of the stitch-forming elements and other means 85 to actuate the couplings and the stitch-forming elements in accordance with the differentiation of the feelers, said means actuating the couplings progressively in the formation of individual rows of stitches and 90 while the knitting is going on continuously, round and round said bank, in one direction.

32. In a knitting machine, a circular bank 95 of stitch-forming elements, a yarn guide therefor, means to move the stitch-forming elements in the formation of stitches, a plurality of pattern feelers arranged in groups, a section of a perforated pattern-controlling element for each of said feeler groups, the perforations thereof being arranged in rows 100 substantially crosswise of the section, a coupling extending from each feeler to control the action of said moving means on a stitch-forming element in accordance with the differentiation of the feelers brought 105 about by feelers moving into pattern perforations, other means to actuate said coupling, means to support each pattern-controlling section in a fixed relation to said bank of stitch-forming elements and the 110 feelers being arranged to move into the perforations thereof and means for advancing the pattern-controlling element sections progressively in the formation of individual rows of stitches and during the movement 115 of the yarn guide in making repeated complete revolutions around the bank of stitch-forming elements in one direction.

33. In a machine for knitting fabrics incorporating designs, the combination with a 115 circular bed of stitch-forming elements, of a plurality of pattern mechanism sections fixed about the axis of said bank, each of said sections comprising a section of a pattern-controlling element, a group of feelers 120 arranged in a row substantially crosswise of the corresponding pattern-controlling element section for call thereby, and a plurality of levers coupling said feelers to said bed to control the action of the stitch-forming 125 elements in accordance with the call of the feelers, other means to actuate said levers, means providing a support for each of said sections of the pattern-controlling element, said supports being substantially fixed in 130

- position with respect to the groups of feelers, and means for advancing the pattern-controlling element sections between their respective supports and the feelers callable 5 thereby, said means advancing the pattern-controlling element sections while knitting is going on around said circular bed continuously in one direction.
34. In a knitting machine for knitting fabrics incorporating designs, the combination with a circular bed of stitch-forming elements and a cam ring rotating thereabout and having a cam to actuate said stitch-forming elements in the formation of 10 stitches, of a pattern mechanism comprising a plurality of sections, each of which sections comprises a section of a pattern-controlling element in the form of an endless belt perforated in accordance with the design to be knit, a group of feelers to simultaneously coat with said belt and individually move into the pattern perforations, a group of levers respectively related to the feelers, means providing a support for the 15 section of the pattern-controlling element, and bracket means for supporting said group of feelers, group of levers, and pattern section support, the various pattern-mechanism sections being arranged around 20 the axis of said bed adjacent said cam ring, and other means carried with said cam ring for advancing all the sections of the pattern-controlling element between their respective supports and feelers to make successive calls 25 on the feelers and for actuating the levers so that they control the actuation of the stitch-forming elements by said stitch-forming element actuating cam in accordance with the call of the pattern-controlling element on the feelers, said sections of the pattern-controlling element being advanced seriatim in the formation of 30 individual rows of stitches and while said cam is actuating stitch-forming elements to form 35 40 45 stitches.
35. In a circular knitting machine the combination with a grooved cylinder and a series of needles and needle-jacks carried by said cylinder, of a plurality of control units 50 arranged circumferentially about the cylinder, each unit comprising a section of a pattern controlling element and a plurality of jack-levers subject to the call of the respective section of the pattern-controlling element and cooperating with said jacks in accordance with said calls, other means to 55 actuate the jack-levers, and means for advancing the pattern sections seriatim with respect to individual passes of a feed of the 60 machine and while said feed is making repeated one-direction revolutions about the needle cylinder.
36. In a circular knitting machine, the combination of a circular bank of stitch-forming elements, a plurality of control 65 units therefor arranged circumferentially around the axis of said bank, each unit comprising a section of a pattern-controlling element, a plurality of feelers subject to the call of the respective section of said pattern-controlling element, and a lever related to each of said feelers, the fulcrums of said levers being fixed in position, means for advancing said sections of the pattern-controlling element to make new calls on the 70 feelers, said sections of the pattern-controlling element being advanced thereby seriatim with respect to individual passes of a feed of the machine and while said feed is making repeated one-direction revolutions about said bank of stitch-forming elements, and a cam revolving with said feed around the axis of said stitch-forming element bank, to turn on their fulcrums those levers, of all the units, which are differentiated by the 75 call of the pattern controlling element on the feelers and thereby cause the desired operation of the corresponding stitch-forming elements.
37. In a knitting machine, a circular bed 80 for stitch-forming elements, a pattern-controlling element, a plurality of feelers for call thereby, couplings relating said feelers to said bed and arranged in groups, other means for actuating as a unit all those couplings of a group which are selected by a call of the pattern-controlling element on the feelers and for holding such actuated couplings in actuated position, and a cam for actuating the stitch-forming elements in accordance with the separation of the selected 85 couplings from the remainder of the couplings which is due to the aforesaid actuation of selected couplings, said coupling actuating means acting on the groups progressively in the formation of individual rows of stitches, in advance of the action of said cam on the corresponding stitch-forming elements, and while the cam is revolving round-and-round the bank of stitch-forming elements continuously in one direction to add a plurality of complete rows of 90 stitches to the fabric, and said coupling holding means being adapted to hold each actuated coupling in actuated position until the said cam has acted upon the last stitch-forming element corresponding to the respective group of couplings.
38. In a circular knitting machine, a circular bed for stitch-forming elements the axis of which is vertical, a pattern-controlling element having the form of an endless belt perforated in accordance with the design to be knitted, a supporting means therefor providing a horizontal axis around which said pattern-controlling element is advanced, feelers to engage with said pattern-controlling element in a substantially vertical direction adjacent said supporting means and enter the perforations therein, couplings re- 95 100 105 110 115 120 125 130

lating the feelers to said bed and controlled by the feelers, and other means to actuate the couplings in accordance with the call of the pattern-controlling element on the feelers to effectuate the control of said element on the stitch-forming elements, said other means acting on the couplings in a substantially horizontal direction.

39. In a knitting machine, the combination of a circular bank of stitch-forming elements, a yarn guide therefor, a pattern-controlling element, a plurality of feelers to bear lightly thereagainst for call thereby, a coupling for coupling each feeler to a stitch-forming element, and other means for actuating said couplings in accordance with the call of the feelers by the pattern-controlling element to effectuate the control of the stitch-forming elements, said means revolving around the axis of said bank at the same rate as said yarn guide and being adapted to actuate all said couplings during each revolution.

40. In a knitting machine, the combination of a circular bank of needles, a pattern-controlling element, a plurality of feelers arranged in a row substantially crosswise of the pattern-controlling element to coact with said pattern element for call thereby, couplings extending from said feelers to said needles, a cam revolving around the needle bank to actuate members of said couplings, when advanced into its path, to cause the corresponding needles to rise to take on yarn, other means for moving the feeler-selected couplings to bring members thereof into the path of said cam progressively subsequent to their selection by the feelers and in advance of said cam while said cam is making repeated complete revolutions about the needle bank, and a stitch cam revolving with but behind the first mentioned cam to retract the raised needles to complete the stitches.

45. 41. In a knitting machine, the combination of a circular bed for stitch-forming elements, a pattern-controlling element, a plurality of feelers which co-act with said pattern-controlling element for call thereby, said feelers and the pattern-calling agencies of the pattern-controlling element being arranged in rows substantially cross-wise of the latter, couplings relating said feelers to said bed for stitch-forming elements, a cam revolving around the axis of said bed to actuate the respective stitch forming elements thereof when members are interposed in its path by corresponding couplings, and other means to actuate the feeler selected couplings to control the interposition of members within the path of said cam, said means actuating said couplings progressively subsequent to their selection by the feelers and in advance of said cam and while said cam is

making repeated complete revolutions about the bank of stitch-forming elements.

42. In a knitting machine the combination with a series of needles and actuating means therefor, of a pattern mechanism, having in combination a recessed platen, a pattern sheet movable over said platen and having perforations movable into registry with a recess in the platen, selectors having feeler fingers arranged to engage the recessed platen through the perforations in the pattern sheet, and means for moving the platen and thereby moving the feelers engaged therewith and the corresponding selectors to differentiate said selectors from the other selectors, the selectors being related to said needle actuating means so that said movement of selectors controls the action of the needles.

43. A pattern mechanism for knitting machines having in combination a recessed platen, a pattern sheet cooperating with said platen and having perforations and a series of selectors movable pivotally and longitudinally and having fingers spring pressed toward said platen and arranged to enter a recess thereof, such selectors as engage the recess through the pattern sheet perforations being moved longitudinally by the platen.

44. A pattern mechanism for knitting machines having in combination a recessed platen, a pattern sheet-cooperating with said platen and having perforations, a series of selectors movable pivotally and longitudinally and having fingers spring-pressed toward said platen and arranged to enter a recess thereof, such selectors as engage the recess through the pattern sheet perforations being moved longitudinally by the platen, stitch controlling levers positioned to be engaged by the selectors when in projected position, a ram cooperating with the projected selectors to actuate the corresponding levers and acting also to retract the feeler fingers from the platen recess, substantially as and for the purpose described.

45. In a knitting machine, the combination of stitch-forming elements arranged in a circular bank, a perforated pattern-controlling element of elongated form, a plurality of feelers adapted to reach into the perforations and thereby be called in various combinations, said feelers and the perforations therefor being arranged in rows substantially crosswise of the pattern-controlling element, and means for coupling the feelers to the stitch-forming elements to control their action, the pattern-controlling element advancing lengthwise to bring successive combinations of pattern perforations to the feelers while said stitch-forming elements are forming stitches, and other means for operating the coupling means and performing the subsequent operations of the

knitting machine consequent on the said calling of the feelers so that the said pattern-controlling element performs substantially only the bare function of directing the knitting processes, said last mentioned means operating simultaneously with the formation of stitches but being timed to exercise its control at different points around the circular machine separately and at each point exercising its control while the knitting is interrupted for the moment at that point.

46. In a circular knitting machine, the combination with a circular bank of stitch-forming elements, of a pattern-controlling element having pattern-calling perforations arranged in rows substantially crosswise of the pattern-controlling element, supporting means for the pattern-controlling element providing an axis fixed in position with respect to the group of feelers, around which said pattern element is advanced to make successive calls on the feelers, a group of feelers for coaction with the pattern element and lightly bearing against the same and arranged to move individually into the perforations in said pattern element, said feelers and supporting means being carried on the knitting machine in juxtaposition to its said circular bank of stitch-forming elements, means for advancing the perforated pattern element between said supporting means and the feeler group to bring successive rows of the perforations to the feelers, coupling means extending from the feelers, and other means including said advancing means for actuating the coupling means as the latter are selected by the action of the perforated pattern element on the feelers.

47. In a circular knitting machine, the combination of a circular bank of stitch-forming elements, a pattern-controlling element therefor, a plurality of feelers which bear only lightly against said element, said feelers and the pattern-calling agencies of the pattern-controlling element being arranged in rows substantially crosswise of the latter, and other means relating each feeler to a stitch-forming element and performing the work of controlling and actuating the stitch-forming elements in accordance with the call of the pattern-controlling element on said feelers, said other means acting round-and-round the bank of stitch-forming elements continuously a number of complete revolutions in one direction.

48. The combination in a circular knitting machine, of a circular bank of stitch-forming elements, a yarn guide therefor, means for revolving the yarn guide around the axis of the bank of stitch-forming elements continuously a number of complete revolutions in one direction, a pattern-controlling element, a plurality of feelers to coact therewith, said feelers and the pattern-calling agencies of the pattern-controlling element

being arranged in rows substantially crosswise of the pattern-controlling element, couplings extending from said feelers to control the action of said stitch-forming elements, and other means to actuate the couplings, 70 said other means actuating couplings while the yarn guide is revolving around said axis a number of complete revolutions continuously in one direction and in accordance with the call of the pattern-controlling element on the feelers to cause the stitch-forming elements to operate in accordance with said call of the pattern-controlling element, and said other means being so timed with respect to the formation of stitches that said 80 other means can actuate each coupling at a time when the respectively corresponding stitch-forming element is not acting in the formation of a stitch and while other stitch-forming elements are acting to form stitches. 85

49. In a knitting machine, the combination of a circular bed for stitch-forming elements, a pattern-controlling element, feelers coacting with said pattern-controlling element for call thereby, the feelers and the pattern-calling agencies of the pattern-controlling element being arranged in rows substantially crosswise of the latter, couplings relating the feelers to said bed to control the operation of the stitch-forming elements, and other means to move those couplings which are to be moved to cause the operation of the stitch-forming elements in accordance with the call of the pattern-controlling element, said other means moving 90 progressively those couplings selected for the knitting of each individual row of stitches and acting round and round the machine continuously a number of complete revolutions in one direction. 95

50. In a knitting machine, the combination of a circular bed for stitch-forming elements, a yarn guide therefor revolving around the axis of said bed, a pattern-controlling element, feelers to coact with said pattern-controlling element for call thereby, said feelers and the pattern-calling agencies of the pattern-controlling element being arranged crosswise of the latter, couplings relating the feelers to said bed and being individually movable to control the operation of the stitch-forming elements, and other means to engage the couplings directly to move those couplings which are to be moved to control the operation of the stitch-forming elements in accordance with the call of the pattern-controlling element, said pattern-controlling element being arranged to bring a new call to a plurality of the feelers 110 simultaneously and being advanced to bring a new call to each such plurality of feelers only once in each revolution of said yarn guide, and said other means moving the selected couplings progressively in each 115 revolution of said yarn guide around the 120

125

axis of said bed, and acting round and round the machine continuously a number of complete revolutions in one direction.

51. In a circular knitting machine, the combination of a circular bed for stitch-forming elements, a yarn guide to revolve repeatedly around the axis of said bed in one direction, a pattern-controlling element, a plurality of feelers to coact therewith, said feelers and the pattern-calling agencies of the pattern-controlling element being arranged in rows substantially crosswise of the latter, couplings, each including a lever, relating the feelers to said bed, the levers being placed substantially radial to and around the axis of said bed for stitch-forming elements and arranged to engage and actuate members in the bed as the couplings are actuated, and other means to actuate the couplings, said other means actuating said levers while the yarn guide is making repeated revolutions around the axis of said bed in one direction and being so timed in its action on the respective levers that each lever to be actuated to affect the formation of a stitch is actuated in advance of the completion of said stitch.

52. In a knitting machine, the combination of a circular bed for stitch-forming elements, a pattern-controlling element, a plurality of feelers to coact therewith, said feelers and the pattern-calling agencies of the pattern-controlling element being arranged in rows substantially crosswise of the latter, couplings, each including a lever, relating the feelers to said bed, said levers being arranged to engage and actuate members in said bed as the couplings are actuated, and other means to actuate the couplings, said other means being so timed in its action on the respective levers that each lever to be actuated to affect the formation of a stitch is actuated in advance of the completion of said stitch.

53. In a circular knitting machine, the combination of a circular bed, stitch-forming elements therein, a pattern-controlling element having its pattern-calling agencies arranged in rows crosswise of itself, a plurality of feelers arranged in a row crosswise of and to coact with said pattern element, couplings relating the feelers to said bed, each of said couplings including a lever arranged substantially radial to the axis of the bed and reaching to the bed to actuate a member therein, other means to actuate progressively the couplings selected by the action of the pattern element on the feelers, a cam revolving around the axis of said bed to retract the stitch-forming elements, and another cam revolving around the axis to return actuated coupling levers.

54. In a knitting machine, the combination of a circular bank of stitch-forming elements, a pattern-controlling element, a

plurality of feelers to coact with said pattern-controlling element, said feelers and the pattern calling agencies of the pattern-controlling element being arranged in rows substantially crosswise of the pattern-controlling element, a lever between each of said feelers and a stitch-forming element through which the control of stitch-forming element is exercised, other means for operating said levers progressively around said bank in accordance with the action of the pattern-controlling element on the feelers, said other means making successive passes around the bank all in one direction while new selections of the levers to be operated by said means are being made, but being so timed as to operate each lever subsequent to the action of the pattern-controlling element on the corresponding feeler, and a cam revolving around the axis of said bank for removing those stitch-forming elements selected by said operation of the levers in a manner to produce a design.

55. In a knitting machine, the combination of a slotted bed, stitch-forming elements in slots thereof, a pattern-controlling element, feelers to coact therewith, said feelers and the pattern-calling agencies of the pattern-controlling element being arranged in rows extending substantially crosswise of the latter, levers laid substantially radially to said bed with their pivot bearings fixed in position with respect to the slotted bed and with one end of each lever extending into a slot in said bed, said end of each lever being related to a stitch-forming element to control the action of the same and the levers being related to said feelers adjacent their opposite ends, and other means for operating the levers in accordance with the call of the pattern-controlling element on the feelers.

56. In a knitting machine, the combination of a circular bed for stitch-forming elements, a yarn guide revolving about the axis of said bed, a cam to actuate members in said bed, also revolving about said axis, a pattern-controlling element having its pattern-calling agencies arranged in rows substantially crosswise of itself, a plurality of levers laid radially around the axis of said bed to move members in said bed into the path of said cam in accordance with the call of the pattern-controlling element and other means to move the levers selected by the pattern-controlling element, turning the levers on their pivots progressively in advance of the cam during individual revolutions of the cam to move the corresponding members in the bed into the path of said cam and while the cam and yarn guide are making a number of complete revolutions about said axis uninterruptedly in one direction.

57. In a knitting machine, the combina-

- tion of a non-revolving circular slotted bed for sliding needles, a yarn guide revolving about the axis of said bed, a cam also revolving about said axis to project members 50 substantially crosswise of the latter, a lever related to each feeler, said levers being distributed around the axis of said circular bank, means to connect each lever to a stitch-forming element, a cam revolving around the axis of said bank, and means to move levers 70 selected by the action of the pattern-controlling element on the feelers into the path of action of said cam for actuation thereby to cause the actuation of the corresponding stitch-forming elements to desired positions. 80
5. In a knitting machine, the combination of a bed for the stitch-forming elements, cam means to move said stitch-forming elements to desired positions, a pattern-controlling element, a plurality of feelers 85 therefor arranged crosswise of the pattern-controlling element, couplings extending from the feelers to said bed and movable to move members lying in said bed into the path of said cam means to permit said cam means to move the stitch-forming elements to said desired positions, and other means to actuate the couplings selected by the action of the pattern-controlling element on the feelers to move the corresponding members 90 into the path of said cam means, the last mentioned means being arranged to move couplings while said cam means is moving stitch-forming elements but being timed to act on each selected coupling at a 100 time when the corresponding stitch-forming element is free of said cam means.
6. In a knitting machine, the combination of a circular bed for the stitch-forming elements, a yarn guide, a cam revolving around the axis of said bed to move the stitch-forming elements, a pattern-controlling element, the pattern-calling agencies 105 of which are arranged in rows substantially crosswise of the pattern-controlling element, couplings outside said bed extending substantially from said pattern-controlling element to said bed, and other means to move said couplings to move members in said bed into the path of said cam, couplings selected by the action of the pattern-controlling element for individual revolutions of the yarn guide being moved progressively and in advance of said cam to bring said members 115 into the path of the latter while the cam makes a number of complete revolutions uninterruptedly.
7. In a circular knitting machine, the combination of a circular bank of stitch-forming elements, jacks for said stitch-forming elements, a pattern-controlling element, feelers therefor arranged crosswise of said pattern-controlling element, couplings connecting individual feelers to individual jacks and other means for actuating the couplings 120 and projecting and retracting all those jacks which are to be actuated to cause the stitch-forming elements to operate in accordance with the call of the pattern-controlling element on the feelers, said other means actuating the selected jacks progressively and acting round and round the machine continuously a number of complete revolutions in one direction.
8. In a knitting machine, the combination of a circular bank of stitch-forming ele-

members sliding in said bed into the path of said cam to permit said cam to project the needles, a cam arranged to retract all said members from the path of the first mentioned cam, and other means acting on said couplings to actuate those couplings selected by the action of the pattern-controlling element on the feelers to move the corresponding sliding members into the path of the first mentioned cam, said means actuating progressively those couplings selected for any single revolution of the yarn-guide and acting while said cams and yarn-guide are revolving uninterruptedly around said bed a number of complete revolutions in one direction.

64. In a knitting machine, the combination of a bed for stitch-forming elements, a pattern-controlling element, a plurality of feelers arranged crosswise thereof, couplings relating the feelers to said bed to move members lying in said bed, a cam to move coupling members, and other means acting on said couplings to move members of the couplings selected by the action of the pattern-controlling element on the feelers, said other means moving those coupling members with respect to the range of action of said cam to permit said cam to move only chosen couplings and thereby move the corresponding members which lie in said bed, and said other means being arranged to actuate coupling members while said cam is moving coupling members but being timed to move each selected coupling member before the cam reaches the same coupling.

65. In a knitting machine, the combination of a circular bank of stitch-forming elements, a pattern-controlling element, a plurality of feelers to coat therewith, said feelers and the pattern-calling agencies of the pattern-controlling element being arranged in rows substantially crosswise of the latter, a bar directly related to each of said feelers and related to and movable to control the action of a stitch-forming element, said bars being turned on their pivots by the action of the pattern-calling agencies on the feelers, and other means to move the bars to effectuate the control, said means acting on those bars which are differentiated from the rest by some of the bars being turned on their pivots.

66. The combination with a knitting machine, including a bed for stitch-forming elements, of a pattern mechanism therefor comprising a pattern-controlling element, a plurality of feelers to coat therewith, said feelers and the pattern-calling agencies of the pattern-controlling element being arranged in rows substantially crosswise of the latter, means including a pivoted member directly related to each of said feelers, said members being thereby adapted to be differentiated among themselves by the ac-

tion of the pattern-calling agencies on the feelers and said means extending to said bed of the knitting machine to control the operation of elements therein, and other means to actuate the first mentioned means as by 70 said pivoted members to cause them to exercise control of the knitting machine operation.

67. In a circular knitting machine, the combination with a circular bank of stitch-forming elements, of a plurality of pattern supports arranged around the axis of said circular bank, each pattern support being provided with longitudinally extending recess means, a pattern sheet for each support having pattern-calling perforations arranged in rows parallel to said recess means of its support, a series of selectors for each support and individually related to the stitch-forming elements to control their operation, said selectors being movable pivotally and longitudinally and having fingers to engage the respective pattern sheet and arranged to pass through its perforations into the recess means in the respective support, 80 and means for moving the supports progressively around the axis of said circular bank, those selectors whose fingers enter recess means in the support by the turning of the selectors on their pivots, having their fingers 90 engaged by the sides of the recess means as the supports are moved and the said selectors thereby being moved longitudinally.

68. In a circular knitting machine, the combination with a circular bank of stitch-forming elements, of a plurality of pattern supports arranged around the axis of said circular bank, each pattern support being provided with a longitudinally extending recess means, a pattern sheet for each support having pattern-calling perforations arranged in rows parallel to said recess means of its support, a series of selectors for each support and individually related to the stitch-forming elements to control their operation, said selectors being movable longitudinally and having fingers to engage the respective pattern sheet and arranged to pass through its perforations into the recess means of the respective support, and means 100 for moving the supports progressively around the axis of said circular bank, those selectors whose fingers enter recess means in the support, having their fingers engaged by sides of the recess means as the supports 105 are moved and the said selectors thereby being moved longitudinally.

69. The combination with a knitting machine in which a bed for stitch-forming elements is fixed in position, of a pattern mechanism for said machine comprising a perforated pattern-controlling element, a plurality of feelers arranged to move into said perforations in a substantially vertical direction, said feelers and the perforations of 110

- the pattern-controlling element being arranged in rows substantially crosswise of the latter, a member directly related to each feeler and pivoted to turn in a substantially 5 vertical plane as its feeler enters a perforation, means to support said pattern-controlling element and the feelers and members adjacent the bed of said machine, and other means to actuate those of said members
- 10 which are differentiated from the rest of the members by the feelers of some of the members entering said perforations, to effectuate the control of the knitting machine operation.
- 15 70. The combination with a circular knitting machine, of a pattern mechanism divided into a number of sections which are distributed around the needle cylinder of said machine and immediately outside the 20 same, each of said sections comprising a pattern-controlling element, a plurality of feelers therefor arranged crosswise thereof, and a plurality of couplings relating said feelers to a circular bed for stitch-forming elements in said machine, and other means for actuating couplings selected in accordance with the call of the pattern-controlling element on the feelers to control the action of the stitch-forming 25 elements in said bed, said other means acting on selected couplings progressively around the cylinder during individual passes of a yarn guide and while said yarn guide is making a number of complete revolutions in one direction uninterruptedly and 30 while stitches are being formed.
- 35 71. In a knitting machine, the combination of a circular bank of stitch-forming elements, a pattern-controlling element, a plurality of feelers to coact therewith, the feelers and the pattern-calling agencies of the pattern-controlling element being arranged in rows substantially crosswise of the latter, a pivoted selector directly related 40 to each feeler and turning on its pivot when
- its feeler encounters one of the pattern-calling agencies, a lever related to each of said selectors to control the operation of a stitch-forming element, said levers being supported radially to the axis of said bank and being 45 substantially uniformly distributed thereabout in juxtaposition to the stitch-forming elements they control, and other means to actuate the selectors and through the selectors to actuate the corresponding levers to 50 cause the latter to exercise their control of the corresponding stitch-forming elements, said means acting on those selectors which are differentiated from the rest by some of the feelers encountering said pattern-calling 55 agencies.
72. In a circular knitting machine, the combination with a circular bank of stitch-forming elements and a cam revolving about the axis of said bank to retract said stitch-forming elements, of a pattern-controlling element, a plurality of feelers to coact with said pattern-controlling element for call thereby, said feelers and the pattern-calling 60 agencies of the pattern-controlling element 70 being arranged in rows substantially crosswise of the latter, couplings between said feelers and stitch-forming elements, a cam revolving about the axis of said bank of stitch-forming elements to actuate members 75 of said couplings when advanced into its path, to cause actuation of the corresponding stitch-forming elements to desired positions, and other means for actuating feeler-selected couplings to control the location of 80 members of the couplings within the path of the last mentioned cam, said means actuating the selected members progressively and in advance of the last mentioned cam while 85 said cams are making repeated complete revolutions about said bank axis in one direction.

ALFRED A. ADLER.
HARRY LIEPMAN.

- the pattern-controlling element being arranged in rows substantially crosswise of the latter, a member directly related to each feeler and pivoted to turn in a substantially 5 vertical plane as its feeler enters a perforation, means to support said pattern-controlling element and the feelers and members adjacent the bed of said machine, and other means to actuate those of said members 10 which are differentiated from the rest of the members by the feelers of some of the members entering said perforations, to effectuate the control of the knitting machine operation.
- 15 70. The combination with a circular knitting machine, of a pattern mechanism divided into a number of sections which are distributed around the needle cylinder of said machine and immediately outside the 20 same, each of said sections comprising a pattern-controlling element, a plurality of feelers therefor arranged crosswise thereof, and a plurality of couplings relating said feelers to a circular bed for stitch-forming elements in said machine, and other means for actuating couplings selected in accordance with the call of the pattern-controlling element on the feelers to control the action of the stitch-forming 25 elements in said bed, said other means acting on selected couplings progressively around the cylinder during individual passes of a yarn guide and while said yarn guide is making a number of complete revolutions in one direction uninterruptedly and 30 while stitches are being formed.
71. In a knitting machine, the combination of a circular bank of stitch-forming elements, a pattern-controlling element, a 35 plurality of feelers to coact therewith, the feelers and the pattern-calling agencies of the pattern-controlling element being arranged in rows substantially crosswise of the latter, a pivoted selector directly related 40 to each feeler and turning on its pivot when
- its feeler encounters one of the pattern-calling agencies, a lever related to each of said selectors to control the operation of a stitch-forming element, said levers being supported radially to the axis of said bank and being 50 substantially uniformly distributed thereabout in juxtaposition to the stitch-forming elements they control, and other means to actuate the selectors and through the selectors to actuate the corresponding levers to 55 cause the latter to exercise their control of the corresponding stitch-forming elements, said means acting on those selectors which are differentiated from the rest by some of the feelers encountering said pattern-calling 60 agencies.
72. In a circular knitting machine, the combination with a circular bank of stitch-forming elements and a cam revolving about the axis of said bank to retract said stitch-forming elements, of a pattern-controlling element, a plurality of feelers to coact with 65 said pattern-controlling element for call thereby, said feelers and the pattern-calling agencies of the pattern-controlling element 70 being arranged in rows substantially crosswise of the latter, couplings between said feelers and stitch-forming elements, a cam revolving about the axis of said bank of stitch-forming elements to actuate members 75 of said couplings when advanced into its path, to cause actuation of the corresponding stitch-forming elements to desired positions, and other means for actuating feeler-selected couplings to control the location of 80 members of the couplings within the path of the last mentioned cam, said means actuating the selected members progressively and in advance of the last mentioned cam while 85 said cams are making repeated complete revolutions about said bank axis in one direction.

ALFRED A. ADLER.
HARRY ALBERTMAN.

CERTIFICATE OF CORRECTION.

Patent No. 1,662,627.

Granted March 13, 1928, to

ALFRED A. ADLER ET AL.

It is hereby certified that error appears in the printed specification of the above numbered patent requiring correction as follows: Page 16, line 70, claim 66, after the word "as" insert the word "differentiated"; and that the said Letters Patent should be read with this correction therein that the same may conform to the record of the case in the Patent Office.

Signed and sealed this 17th day of April, A. D. 1928.

(Seal)

M. J. Moore,
Acting Commissioner of Patents.
